SPOOL FOR WIRE, CHAIN, EXTRUDED TUBING,
ROPE, STRING AND PAPER COVERED WIRE
TWIST TIES

George C. Anderson, 2425 SE. Moores St.,
Portland, Oreg. 97202

Filed May 16, 1968, Ser. No. 11,967

Term of patent 14 years

Int. Cl. D8—03

U.S. Cl. D8—220

The single figure of the drawing is a perspective view of the spool for wire, chain, extruded tubing, rope, string and paper covered wire twist ties of my invention, showing one side thereof, the reverse side being identical to the side shown.

I claim:

The ornamental design for a spool for wire, chain, extruded tubing, rope, string and paper covered wire twist ties, as shown and described.
